UNITED STATES PATENT OFFICE.

WILLIAM SCHUMACHER, OF BROOKLYN, NEW YORK.

DESIGN FOR AN ALTO-RILIEVO.

SPECIFICATION forming part of Design No. 14,041, dated July 3, 1883.

Application filed May 14, 1883. Term of patent 3½ years.

To all whom it may concern:

Be it known that I, WILLIAM SCHUMACHER, of Brooklyn, in the county of Kings and State of New York, have invented a new and original Design for Alto-Rilievo, of which the following is a full, clear, and exact description, reference being had to the accompanying drawing, which fully shows the nature of my invention.

10 My invention relates to an improved design for an alto-rilievo; and it consists of an oblong block or plate having a raised representation of the New York and Brooklyn suspension-bridge, a depressed panel below said representation, and a raised border.

15 A represents an oblong block or plate of suitable material, upon the face of which is arranged a perspective representation, B, of the New York and Brooklyn suspension-bridge.

20 A narrow depressed panel, C, extends along the lower part of said representation. A raised border, D, extends around the block or plate A, and forms thereby a kind of frame, within which the representation of said bridge and

25 the panel below the same are arranged. The

whole is intended to be a memento of the opening of said bridge for use.

Having thus described my invention, I claim as new and desire to secure by Letters Patent—

1. A design for an alto-rilievo, composed of 30 an oblong block or plate having a raised border and a raised representation of the New York and Brooklyn suspension-bridge within said border, substantially as shown and described.

2. A design for an alto-rilievo, consisting of 35 an oblong block or plate, a raised representation of the New York and Brooklyn suspension-bridge, a depressed panel below said representation, and a raised border or frame extending around said representation and panel, 40 substantially as shown and described.

In testimony that I claim the foregoing as my invention I have signed it this 10th day of May, 1883.

WILLIAM SCHUMACHER.
